(57) **CLAIM**

The ornamental design for a flush rivet laminated pliers, as shown and described.

DESCRIPTION

FIG. 1 is a perspective view of flush rivet laminated pliers showing my new design;

FIG. 2 is a front view of the pliers.

FIG. 3 is a rear view of the pliers.

FIG. 4 is a side view of the pliers.

FIG. 5 is an opposite side view of the pliers.

FIG. 6 is a bottom view of the pliers, and,

FIG. 7 is a top view of the pliers.

The broken lines immediately adjacent the shaded areas represent the bounds of the claim and all other broken lines are for illustrative purposes only. None of the broken lines form a part of the claimed design.
